PITCHING MACHINE

Heinrich Beckschulte, Angola, N. Y., assignor to
Enzinger Union Corporation, Buffalo, N. Y.

Application October 11, 1934, Serial No. 747,911

9 Claims. (Cl. 91—11)

This invention relates to improvements in pitching apparatus of the kind commonly employed for use in pitching kegs, barrels or other containers.

5 The objects of this invention are to provide an apparatus of this kind by means of which the operations of pitching containers may be more easily and efficiently carried out; also to provide an apparatus of this kind with means of improved construction for melting and removing the old pitch in a container prior to repitching the same; also to provide an apparatus of this kind with means, whereby products of combustion from a pitching apparatus can be used for 10 melting old pitch within a container.

Other objects of this invention are to provide improved means for removing the fumes of the pitch after the pitching of a container; also to provide an apparatus of this kind in which the 15 pitch fumes may be removed from a freshly pitched container by discharging products of combustion into the same.

Further objects of this invention are to provide a pitching apparatus with a combustion chamber into which a kettle or container for pitch extends, and in which the heat contained in the products of combustion after heating the kettle may be utilized for depitching containers; also to provide the combustion chamber of a 20 pitching apparatus with a coil or duct through which the products of combustion pass after they have contacted with the kettle, to impart additional heat to the products of combustion for melting old pitch in a container; also to improve apparatus of this kind in other respects herein- 25 after specified.

In the accompanying drawings:

Fig. 1 is a top plan view of a pitching apparatus embodying this invention.

40 Fig. 2 is a sectional plan view thereof on line 2—2, Fig. 6.

Fig. 3 is a fragmentary, sectional plan view thereof on line 3—3, Fig. 6.

Fig. 4 is a fragmentary, sectional view on an 45 enlarged scale on line 4—4, Fig. 1, showing a nozzle for discharging heated products of combustion into a container for depitching.

Fig. 5 is an elevation of the nozzle shown in Fig. 4 and showing the positions of the parts 50 when the container is removed from the nozzle.

Fig. 6 is a longitudinal sectional elevation of my improved pitching apparatus, on an enlarged scale, on line 6—6, Fig. 1.

Fig. 7 is a transverse sectional elevation on 55 line 7—7, Fig. 1.

Fig. 8 is a central sectional elevation of a combined pitch spraying and defuming nozzle.

Fig. 9 is a fragmentary top plan view showing the combined pitching and defuming nozzle and the mechanism for rotating the same. 5

Fig. 10 is a fragmentary elevation showing the gearing connecting the motor shaft and the shaft which imparts rotary movement to the pitching and defuming nozzles.

Fig. 11 is a fragmentary sectional view on an 10 enlarged scale on line 11—11, Fig. 1 showing the means for moving the pitching and defuming nozzle into and out of its operative position.

Fig. 12 is a fragmentary sectional view similar to the upper portion of Fig. 11 but showing 15 the parts of the mechanism in different positions.

Fig. 13 is a fragmentary section on line 13—13, Fig. 12.

Fig. 14 is a section on line 14—14, Fig. 8.

The improvements forming the subject matter 20 of my invention are shown in the accompanying drawings as applied to a well known type of pitching apparatus, but it will be understood that this apparatus is shown only for the purpose of illustrating the application of my invention to a 25 complete pitching apparatus and it is not intended hereby to limit this invention to be used only in connection with the particular type of pitching apparatus shown, since it will be obvious that my improvements may be applied to any desired 30 type of pitching apparatus.

The pitching apparatus includes the usual 35 pitching kettle A containing a pump B having discharge ducts 15 for the liquid molten pitch and which lead to the pitch spraying nozzles. 35 The centrifugal pump may be driven by means of a motor 16 through a suitable drive shaft 17 connected by means of beveled gears shown in broken lines in Fig. 1, with the upright shaft of the pump B. X represents the kegs or containers which are operated upon. The kettle A, the pump and the driving mechanism therefor have heretofore been used in connection with pitching apparatus and of themselves form no part of this invention. 45

The pitch kettle extends into the top of a furnace or combustion chamber in which fuel of any suitable kind may be burned to heat the kettle and the pitch contained therein.

The combustion chamber or furnace may be 50 provided on its exterior with a suitable shell 19 which may be made of sheet metal and a lining 20 of fire brick or other refractory and heat insulating material is preferably provided. In the particular construction shown, the combus- 55

tion chamber is heated by gas, and a series of burner pipes 21, 22 and 23 are shown which have apertures through which the gas may be discharged, these burner pipes receiving gas from a feed pipe or conduit 24 arranged on the exterior of the combustion chamber and the supply of fuel may be controlled by means of suitable valves 25. It will be understood, however, that burners for oil or other liquid fuel may be employed, or if desired, solid fuel may be used for heating the combustion chamber.

The necessary air for supporting combustion preferably enters the lower part of the combustion chamber through a series of air openings or ports 26 in the bottom of the combustion chamber. The combustion chamber is provided near its upper portion with a flue 27 for the products of combustion and this flue connects with a chimney 28. The hot gases discharged from the flue 27 may be conducted directly to suitable depitching nozzles, or if preferred, these flue gases may be heated to a still higher temperature to facilitate the removal of old pitch from the containers and in the construction illustrated, an arrangement for adding heat to the flue gases is shown. For this purpose, the chimney 28 is provided with a downwardly extending portion 29 terminating in the inlet of a fan or blower 30 having a discharge duct 31 which extends through an aperture in the outer wall of the furnace or combustion chamber and terminates in an upright passage 32 leading to a re heater arranged in the combustion chamber below the pitch kettle A. This re heater may be of any suitable or desired form and is shown as formed of refractory material which becomes heated from the flames of the burners 21 and 22, which are located below the re heater structure. This re heater has a passage or duct 33, one end of which connects with the upright passage 32 and the other end of which connects with a passage 34, which is circuitous and terminates at its other end in a discharge duct 35 for the heated products of combustion.

The flue pipe 27 is provided with a downwardly extending air inlet pipe or duct 36 controlled by means of a valve or damper 37. The flue pipe 27 also has a valve 38, and a valve 39 is provided in the chimney 28. An additional valve 40 is provided in the portion or extension 29 of the chimney leading to the air intake of the fan 30. By means of these various valves, it will be clear that either products of combustion or a mixture of products of combustion with outside air may be supplied to the re heater in the combustion chamber. When these dampers are set as shown in Fig. 6, it will be obvious that only products of combustion will be passed through the re heater. By partly opening the damper 37 outside air may be admitted through the flue pipe 27 so that a mixture of products of combustion and outside air will pass to the blower. In order to use the combustion chamber for a preliminary heating of the kettle A and the re heater, the dampers 38 and 39 are open and the dampers 37 and 40 are closed, and the fan is not operated, in which case the products of combustion will pass out through the chimney. After the pitch has been melted and the walls of the re heater raised to the desired temperature, the use of the pitching apparatus may be started, and the motor 46 which drives the blower is then started and the dampers may be set into the positions shown in Fig. 6. If the products of combustion discharged into the containers are too hot, the dampers 37 and 38 may be regulated as desired.

The re heater shown has a lower arch shaped wall 41 and an upper substantially flat wall 42 and a series of upright walls 43, all of these walls being arranged to form the passages 33 and 34 in the re heater. The re heater is spaced from an end wall of the furnace or combustion chamber forming a space 44 through which products of combustion from the burners 21 and 22 may pass to the space above the re heater into contact with the kettle A. The re heater may also be provided with an upright passage 45 in which the burner pipes 23 are arranged, so that heat from the burners 21 and 22 may also pass through the passage 45 to heat the kettle A. One or the other of these passages 44 and 45 may, however, be omitted if desired, and a re heater of other construction may be provided.

Referring particularly to Fig. 1, the duct 35 leads to a pair of branch pipes or ducts 59 and 51 terminating in nozzles for discharging gas heated 20 in the re heater, which gas may be products of combustion or a mixture of products of combustion and air, to containers X and another branch pipe 52 is provided which extends toward the other side of the pitching apparatus and dis- 25 charges products of combustion through another pair of branch pipes 53 and 54 leading to another pair of discharge nozzles. The discharge nozzles may also be of any suitable or desired form, and in the construction illustrated, consist merely of 30 short lengths of pipe 56, the lower ends of which connect with one or other of the ducts to receive hot products of combustion therefrom. Each nozzle 56 also is provided with a support for a container, the support 57 shown being in the form 35 of a pan or receptacle for receiving pitch dis- charged from a container. The receptacle is so formed at its upper open end as to support a keg or container X and is provided with a discharge opening 58 near the lower end thereof for the 40 melted pitch. Near its upper portion, the support is provided with openings 59 through which products of combustion discharged from the container through the bung hole y therein may pass. Consequently, when a keg or container is placed 45 into operative position on the container support or receptacle 57 so that the discharge nozzle 56 extends into the bung hole y of the container, hot products of combustion will be blown into the interior of the container and, after heating 50 the pitch lining of the container, will be discharged through the bung hole about the nozzle 56 and will pass out through the apertures 59 in the container support 57. When the pitch within 55 the container becomes sufficiently heated to liquefy the same, it will also run out through the bung hole y about the nozzle 56 into the receptacle 57 from which it is discharged through the aperture 58.

Means are preferably provided for automatically interrupting the flow of heated products of combustion with or without admixture of air through the nozzle 56 when the container is removed from its support 57 and for automatically discharging heated products of combustion into 65 the container when it is positioned upon the container support. Any suitable or convenient means may be provided for this purpose and in the construction shown, each branch pipe leading to a discharge nozzle 56 is provided with a 70 damper or valve 60 having a pivot pin 61 extending through the branch pipe and having a crank arm 62 secured thereto. The crank arm 62 may be pivotally connected to a rod 63, the upper end of which extends into a position to be engaged by 75

5 a container positioned on the support 51. For this purpose, the rod 63 may be slidably mounted on brackets 64 and a spring 65 engaging a collar 66 secured to the rod 63 normally urges the rod into its upper position, as shown in Fig. 5, in which position the valve 60 is closed. In this closed position, the upper end of the rod 63 also extends upwardly beyond the upper edge of the container support 51, and consequently, when a 10 container is positioned upon the support, the rod 63 will be moved downwardly into the valve opening position as shown in Fig. 4.

15 After the old pitch has been removed from the containers by means of the mechanism which has been described, they may be placed in operative relation to either of the two pitching nozzles 10 which are arranged over the pitch kettle A. These nozzles are hollow and are provided at their upper ends with slots 71 through which the 20 pitch may be discharged and the nozzles are preferably rotated while pitch is discharged through the same. Any suitable means for rotating the nozzles may be provided, and in the construction illustrated, this is preferably accomplished 25 through suitable gearing driven by the same motor 16 which also operates the pitch pump B. The shaft 17 of this motor has a gear 73 mounted thereon, see Figs. 9 and 10, and this gear meshes with an idler gear 14, which in turn 30 meshes with a gear 75 mounted on a shaft 76. The shaft 76 has two worms 77 secured thereto and the pitching nozzles 10 have worm gears 78 secured thereto so that the nozzles may be rotated from the motor shaft when the gears of the 35 nozzles 78 mesh with the worms 77.

40 The nozzles 10 are arranged to be moved vertically inwardly and outwardly with reference to the containers and for this purpose, each nozzle is provided with a guide member 80 suitably mounted on the cover or top 81 of the pitch kettle. The guide support 80 is also provided with a channel 82, which in turn connects with a pitch discharge duct 15 leading from the pitch pump B. The nozzles are closed at their lower 45 ends, for example, by means of screw plugs 83 and are provided in their sides with a plurality of apertures or slots 84 which are so arranged that when a pitching nozzle is in its upper or pitching position, the slots 84 will register with the pitch passage 82 in the guide bracket 80, so that pitch from the passage 82 will flow into the hollow interior of the pitching nozzle 10 and will consequently be discharged through the slot 71 in the nozzle. When a nozzle is in its elevated position 50 as shown in the right hand side of Fig. 6, its worm gear 78 meshes with a worm 77, so that the nozzle while discharging pitch is also being rotated about its vertical axis. When a pitching nozzle is in its lower or non-pitching position as shown in the left of Fig. 6 and in Fig. 11, the gear 78 of such nozzle moves downwardly out of engagement with the worm 77, and the slots 84 also move down below the guide bracket 80, so that molten pitch contained within the nozzle 55 may discharge out of the slots 84 into the kettle A.

60 The pitching nozzles may be raised and lowered in any suitable or desired manner, and in the construction illustrated a handle 86 is provided for each nozzle, which extends into the pitch kettle A as clearly shown in Figs. 11 and 12, and which is movably secured to the lower end of a pitching nozzle. The handle is provided with a pin 87 which may rest upon a shoulder 88 formed on one end of a lever 89 pivoted at 90. An arm 75 91 of the lever extends into a position to be en-

gaged by a container placed in operative relation to the pitching nozzle. When this lever is swung by the weight of the container X, the pin 87 may rest on the shoulder 88. When, however, the container X is removed from its position over a 5 pitching nozzle, a counterweight 92 of the lever 89 causes this lever to move into the position shown in Fig. 12, in which the pin 87 will be disengaged from the shoulder 88, thus causing the handle 86 to drop and lower the pitching nozzle 10 to avoid the spraying of molten pitch when a container is not in a position over the nozzle. Preferably, the weight 92 has a notch 93 which engages with the pin 87 when the lever 89 is in the position shown in Fig. 12, in which case the handle 15 86 cannot be moved upwardly until a container is again placed in operative relation to the nozzle 10. 94 represents a guide strap for the handle 86. Any other means for actuating a pitching nozzle may, however, be employed in 20 place of those described.

25 Each of the pitching nozzles is preferably provided with means whereby a defuming agent, such as air or products of combustion, may be discharged into a container after pitching to remove 25 fumes remaining in the container. In the particular construction shown for this purpose, each pitching nozzle is provided with a second passage or duct 95 formed therein and which opens at its upper end in the outer end of the pitching nozzle and the lower end of which has a lateral opening 96 in a side wall of the nozzle. This lateral opening 96 is adapted to register with a stationary 30 passage 97 formed in a second bracket 98 for the pitching nozzle. The passages 97 and the lateral 35 opening 96 of the air duct 95 are so arranged relatively to each other as to be in registration only when the pitching nozzle is in its lowest or non-pitching position. Air or products of combustion may be supplied to the duct or passage 97 40 in any suitable or desired manner. In the construction illustrated in Figs. 1 and 6, a tube or pipe 100 leads to the passage 97 in the bracket 98 and is provided with a valve 101 which may be actuated in any suitable manner when it is desired to admit 45 a defuming medium into the container. This pipe 100 is connected in the particular construction shown with a pipe 102, which in turn connects with a duct carrying hot products of combustion. The pipe 100 may also be connected with a second 50 pipe 103 from a source of compressed air, not shown. The compressed air is controlled by means of a valve 104. A valve or damper 105 is arranged in the pipe 102. With this arrangement either hot products of combustion may be discharged for a short interval of time into a freshly 55 pitched container to discharge fumes from the container or, if preferred, compressed air from any suitable source may be admitted to the pitching nozzle. 60

65 By means of the arrangement on the pitching nozzles of ducts for a defuming medium, the operation of the apparatus is materially simplified since the two operations of pitching and defuming can be carried on without moving the keg or container from one nozzle to another. Upon the completing of the pitching, the container can be instantly defumed by actuating the valve 101.

70 I claim as my invention:

75 1. In a container pitching apparatus, the combination of a combustion chamber in which fuel may be burned, a kettle for pitch extending into said combustion chamber, a nozzle adapted to extend into a container, a heater duct in said combustion chamber and adapted to receive products 75

of combustion after the same have been exposed to said kettle, and means for discharging products of combustion from said heater duct to said nozzle.

- 5 2. In a container pitching apparatus, the combination of a kettle for pitch, a combustion chamber into which said kettle extends and in which fuel may be burned, a heater duct arranged in said combustion chamber, a blower for with-
10 drawing products of combustion from said combustion chamber and passing the same into said heater duct, and means for discharging products of combustion from said heater duct into a container, for melting pitch within said container.
- 15 3. A container pitching machine having a nozzle through which molten pitch may be discharged into a container, a pump for discharging pitch to said nozzle, means for moving said nozzle lengthwise into a container into a position to receive pitch from said pump and discharge the pitch into the container, and into another position in which the discharge of pitch to said nozzle is interrupted, a duct in said nozzle through which a defuming agent may be discharged into a container, and means actuated by the movement of said nozzle into a position to interrupt the discharge of pitch for admitting a defuming agent to said duct only when said pitching nozzle is disconnected from the supply of molten pitch.
- 20 4. In a container pitching machine, a combina-
25 tion of a nozzle having apertures in a side thereof, a part surrounding said nozzle and having a passage through which molten pitch may pass, means for moving said nozzle in a direction for insert-
30 ing the discharge end thereof in a container, said apertures in the side of said nozzle registering with said passage when said nozzle is in its inserted position, means for rotating said nozzle during the discharge of pitch therefrom, a duct
35 in said nozzle through which a defuming medium may be passed into said container when said nozzle is in position to interrupt the discharge of pitch.
- 40 5. In a pitching machine, the combination of a hollow discharge nozzle for molten pitch, guide means in which said nozzle is mounted to move inwardly with reference to a container to be pitched, a passage for pitch arranged in said guide means, apertures in the side of said nozzle adapted
45 to register with said pitch passage in said guide means for permitting pitch to be discharged through said nozzle when said apertures are in operative relation to said passage, a duct in said nozzle terminating at one end in the discharge
50 end of said nozzle and terminating at its other end in a side of said nozzle, and a passage for a

defuming medium arranged to be in registration with said duct in said nozzle when said nozzle is in a position in which said apertures in the side thereof are out of alinement with the pitch passage in said guide means.

5 6. A pitching nozzle having a passage therein for pitch and a duct for a defuming medium, both said passage and said duct terminating in the outer end of said nozzle, means for moving said nozzle inwardly and outwardly relatively to a 10 container, means for supplying pitch to said nozzle when the same is moved into a container, and means for interrupting the supply of pitch to said nozzle when the same is moved outwardly relatively to said container, and means for supply-
15 ing a defuming agent to said nozzle when the same is moved outwardly relatively to said container.

7. In a container pitching apparatus, the combination of a substantially closed combustion 20 chamber in which fuel may be burned, a kettle for pitch extending into said combustion chamber, a heater duct in said combustion chamber, means for passing products of combustion from said combustion chamber through said duct for im-
25 parting additional heat thereto, means for adding outside air to the products of combustion passed to said duct, a nozzle adapted to be inserted into a container, and means for discharging gases from said heater duct to said nozzle for melting 30 pitch within said container.

8. In a container pitching apparatus, the combination of a substantially closed combustion chamber in which fuel may be burned, a kettle for pitch extending into said combustion chamber, a heater duct in said combustion chamber, a passage leading from said combustion chamber to said duct and having an inlet for admitting outside air into said passage, means for regulat-
35 ing the admission of outside air through said 40 inlet to said passage, and means for discharging gases from said heater to a container.

9. A nozzle for spraying pitch into the interior of a container, said nozzle having a passage for pitch and a duct for a defuming agent, both said 45 passage and said duct terminating at the end of said nozzle, means for rotating said nozzle to discharge pitch to all parts of the interior of the container, means for supplying a defuming agent to said duct in said nozzle only when the supply 50 of pitch to said nozzle is interrupted, and means for moving said nozzle in the direction of its length for placing either said passage or said duct into position to receive pitch or defuming agent respec-
55 tively.

HEINRICH BECKSCHULTE.
